CLAIM

The ornamental design for a liquid collection and storage container, substantially as shown and described.

DESCRIPTION

FIG. 1 is a perspective view of the liquid collection and storage container of my new design, as viewed from the top side thereof;

FIG. 2 is a top plan view of the liquid collection and storage container of FIG. 1;

FIG. 3 is a bottom plan view of FIG. 2;

FIG. 4 is a side elevational view of the right side of FIG. 2, the left side being a mirror image thereof;

FIG. 5 is an elevational view of the bottom end of FIG. 2; and

FIG. 6 is an elevational view of the top end of FIG. 2.
